TRIALKYLACETAMIDES HAVING SATURATED ALKYL GROUPS AND A METHOD OF MAKING THE SAME

Karl Junkmann, Berlin, and Hans-Georg Allardt, Philippsthal, Kreis Teltow, Germany, assignors to Schering Aktiengesellschaft, a corporation of Germany

No Drawing. Application January 8, 1937,
Serial No. 119,658. In Germany August 16,
1934

10 Claims. (Cl. 260—561)

This invention relates to trialkylacetamides having saturated alkyl groups and a method of making the same.

By the researches of Fromherz, Arch. f. exp. Pathologie und Pharmakologie, vol. 173, page 78, it has become known that the substituted acetamides possess peripheral paralysing (spasmolytic) properties. This assertion is accompanied on page 83 by three examples, which are, however, only very weakly active acetamides.

The present invention is based on the discovery that the tertiary saturated alkyl substituted acetic acid amides with from 12 to 17 C-atoms, manufactured according to known processes from tertiary nitriles of the general formula:

in which R, R' and R'' indicate the same or different saturated alkyl groups such that in the case of the saturated trialkylacetamides with 12 carbon atoms R, R' and R'' constitute alkyls with at least 3 carbon atoms, compared with those described by Fromherz exhibit an unexpectedly good spasmolytic action.

By comparing the different trialkylacetamides on a superior rabbit intestine maintained permanently in Tyrode solution containing barium, the individual preparations being standardised against novocaine hydrochloride as comparative preparation, the following results are obtained:

Acetamide examined	C-number	Activity number papaverine HCl-solution=100
<i>III. Saturated trialkylacetamides containing 12-17 C-atoms (according to the invention)</i>		
Dipropyl-butyl-acetamide	12	100
Propyl-diethyl-acetamide	13	110
Tributyl-acetamide	14	130
Ethyl-di-isomethyl-acetamide	14	187.5
Ethyl-dihexyl-acetamide	16	125.0
Tri-isoamyl-acetamide	17	125.0
Propyl-diamyl-acetamide	15	125.0
Butyl-diamyl-acetamide	16	118.0
Dibutyl-amyl-acetamide	15	115.0

In these experiments novocaine hydrochloride was equal to 1/75 papaverine hydrochloride. It was therefore possible by a simple calculation to bring the numbers obtained into relation with those given by Fromherz, who uses papaverine as standard and makes this equal to 100.

From this table it is clearly seen that the strong effects obtained with the tertiary saturated amides of this invention were not to be foreseen.

In addition it should be remarked that the hitherto known acetamides with small C-number examined by Fromherz are fairly strong soporifics, while the new substances according to the present invention even in large doses have practically no soporific effect which is extremely essential for clinical application.

The manufacture of the amides of this invention takes place in the known manner by way of the nitriles which can be obtained, for example, according to the processes of the Germ. Patents Nos. 570,594, 581,728, 538,561.

The following examples illustrate the invention the parts being by weight:

Example 1

(a) 10 parts of di-n-butyl-n-propyl-acetonitrile, B. P. 133° C. under 18 mm. pressure and 100 parts of 96% sulphuric acid are heated to 50° C. to the completion of the hydrolysis. The reaction product is poured into ice and the oil separating extracted with a solvent immiscible with water, for example, benzene, the extract washed with sodium carbonate solution and the amide produced therefrom in the customary man-

35	Acetamide examined	C-number	Activity number papaverine HCl-solution=100
<i>I. Saturated trialkylacetamides containing up to 12-C-atoms</i>			
Methyl-diethyl-acetamide	7	0.25	
Triethyl-acetamide	8	0.15	
Diethyl-n-propyl-acetamide	9	2	
Methyl-dipropyl-acetamide	9	2.5	
Ethyl-dipropyl-acetamide	10	8	
Diethyl-butyl-acetamide	10	7	
Tripropyl-acetamide	11	21	
Ethyl-dibutylacetamides	12	12.5	
<i>II. Unsaturated trialkylacetamides containing up to 12-C-atoms</i>			
Diethyl-allyl-acetamide	9	0.6	
Methyl-diallyl-acetamide	9	0.6	
Ethyl-diallyl-acetamide	10	2.5	
n-Propyl-diallyl-acetamide	11	7.5	
Isopropyl-diallyl-acetamide	11	3.75	
n-Butyl-diallyl-acetamide	12	10.0	
Triallyl-acetamide	11	3.5	

5 ner. It is separated from small quantities of starting material by vacuum distillation. The amide has the B. P. 176° C. under 16 mm. pressure, the M. P. 69 to 70° C. and constitutes a white crystal powder which easily dissolves in ether, alcohol, petrol-ether and benzene.

$C_{13}H_{27}ON$

Found.....	% 73.47	% 12.8	% 6.9
Calculated.....	73.2	12.75	6.56

15 The hydrolysis can be carried out instead of with sulphuric acid by heating with water to 180 to 200° C., if desired with the addition of an emulsifying agent such as the sodium salt of di-isopropynaphthalene- β -sulphonic acid.

20 (b) 19.5 parts of di-n-butyl-n-propyl-aceto-
nitrile are dissolved in 200 parts of alcohol and 48 parts of 10% hydrogen peroxide and 0.8 part of caustic soda in a little water added. The whole is heated with stirring gradually to 40 to

25 60° C., neutralised after completion of the hydrolysis with acid and the alcohol evaporated. The residue recrystallised from dilute alcohol yields white needles of M. P. 69-70° C., the pure di-
butyl-propyl-acetamide.

30

Example 2

35 50 parts of tri-n-butyl-acetonitrile B. P. 142 to 146° C. under 17 mm. pressure, 300 parts of butyl or amyl alcohol and 60 parts of potassium hydroxide in 10 parts of water are boiled with stirring under a reflux condenser for 100 hours, the alcohol is thereupon removed by steam distillation and the residue extracted with benzene. From the benzene solution is obtained in the 40 customary manner the amide, which passes over in a vacuum of 12 mm. at 183° C. It solidifies to white needles which have the M. P. 60 to 61° C. It is easily soluble in ether, petrol-ether benzene, alcohol, and chloroform, insoluble in water.

45 $C_{14}H_{29}ON$

50	C	H	N	O

Calculated.....	73.95	12.87	6.16	7.04

55 For acceleration of the saponification it can be carried out suitably in autoclaves at a temperature of 150 to 160° C. Otherwise the process is conducted as set forth above.

Example 3

60 Triisoamyl acetonitrile, obtained according to U. S. Patent 1,958,653 from acetonitrile, sodium amide and isoamyl bromide, yields on saponification triisoamyl acetamide of the boiling point 198° C. at a vacuum of 14 mm. and the melting point 67 to 68.5° C. It crystallizes from petrol ether in white platelets.

65 Of course, in a similar manner other saturated trialkylacetamides having at least 12 and at most 17 carbon atoms in the molecule may be obtained from the corresponding trialkylacetonitriles.

70 What we claim is:

1. A process for the manufacture of a trialkylacetamide with saturated alkyl groups and of strong spasmolytic action, comprising saponifying tri-n-butyl acetonitrile to the corresponding acetamide.

2. Tri-n-butyl acetamide of the general formula $C_{14}H_{29}ON$ and the melting point 60-61° C.

3. A process for the manufacture of substances having a high spasmolytic action, comprising hydrolyzing tertiary nitriles with at least 12 and at most 17 carbon atoms in the molecule, of the general formula:

in which R, R' and R'' indicate saturated alkyl groups all higher than methyl, to the corresponding trialkyl-substituted acetamides, R, R' and R'' in the case of the saturated trialkylacetone-nitriles with 12 carbon atoms constituting alkyls with at least 3 carbon atoms each.

4. A trialkylacetamide of strong spasmolytic action, having at least 12 and at most 17 carbon atoms in the molecule, of the general formula:

in which R, R' and R'' indicate saturated alkyl groups all higher than methyl, at least two of such groups having at least four carbon atoms.

5. A trialkylacetamide of strong spasmolytic action having at least 12 and at most 17 carbon atoms in the molecule, and of the general formula:

in which R, R' and R'' indicate saturated alkyl groups, at least two of such groups having at least four carbon atoms.

6. As a spasmolytic agent, and trialkylacetamide of strong spasmolytic action having more than 12 but no more than 17 carbon atoms in the molecule, and of the general formula:

in which R, R' and R'' indicate saturated alkyl groups all higher than methyl.

7. A trialkylacetamide of strong spasmolytic action of the general formula:

in which R, R' and R'' indicate saturated alkyl groups, at least two of such groups having each at least 4 carbon atoms and the third at least 3 carbon atoms, the total number of carbon atoms in the compound not exceeding 17.

8. A trialkylacetamide of strong spasmolytic action of the general formula:

in which R, R' and R'' indicate saturated alkyl groups of 3 to 5 carbon atoms, at least two of such groups having more than 3 but no more than 5 carbon atoms.

9. As a spasmolytic agent, n-propyl-di-n-butyl acetamide of the general formula $C_{13}H_{27}ON$ and the melting point 69-70° C. from dilute alcohol.

10. As a spasmolytic agent, tri-isoamyl acetamide of the general formula $C_{17}H_{35}ON$ and the melting point 67-68.5° C.

KARL JUNKMANN.

HANS-GEORG ALLARDT. 75
